[57] CLAIM

The ornamental design for a bottle, as shown and described.

DESCRIPTION

FIG. 1 is a perspective view of the bottle showing our new design;

FIG. 2 is a front elevational view thereof, the rear elevational view is the same;

FIG. 3 is a side elevational view thereof, the opposite side is the same;

FIG. 4 is a top plan view thereof; and,
FIG. 5 is a bottom plan view thereof.

The broken lines showing a circular element in FIG. 5 and an arcuate line on the lower portion of the design in FIGS. 1, 2 and 3 are for illustrative purposes only and do not form part of the claimed design.
